UNITED STATES PATENT OFFICE.

CHARLES F. MASON, OF CORTLAND, NEW YORK.

GAS-LIGHTING DEVICE.

1,127,476.

Specification of Letters Patent.

Patented Feb. 9, 1915.

Application filed May 7, 1910. Serial No. 559,902.

To all whom it may concern:

Be it known that I, CHARLES F. MASON, a citizen of the United States, and a resident of Cortland, Cortland county, State of New York, have invented certain new and useful Improvements in Gas-Lighting Devices, of which the following is a specification.

This invention relates to gas lighting devices with particular reference to systems in which the lighting or extinguishing of a number of lamps may be controlled from a single remote point, as, for example, the gas supply station.

In a former patent to me, No. 733,667, July 14, 1903, there is disclosed an automatic gas lighting device located between a gas burner and the supply pipe therefor and operable by the passage of gas through said device to the burner, the lighting being effected by merely turning on the pressure and extinguished by shutting off the same. Obviously lamps such as described in said patent may be controlled individually by providing each with a separate cock, but inasmuch as one of the purposes of the invention is to save the expense of attendants, they are preferably controlled collectively by opening and closing a single valve located at the central or supply station, with the result that the entire system of lamps will be caused to burn at the same time and be extinguished at the same time; and no variation of this condition may be had without the use of separate mains.

The object of the present invention is to provide a simple and efficient mechanism whereby special lamps designed to be controlled from a central station so as to be lighted and extinguished at regular predetermined intervals, such as street lamps, and other lamps not designed to be so controlled such as those used in private houses, may be fed from a common main carrying a continuous supply of gas. This and other objects of the invention will in part be obvious and in part explained in the following description. The invention consists in the novel improvements, parts, and combinations of parts herein shown and described.

In the accompanying drawings, which form a part of this specification, is illustrated one embodiment of the invention, the same serving to exemplify the principles thereof.

Of the drawings: Figure 1 is a central vertical sectional view of a device embodying my invention, and showing the parts in the position they assume before lighting; Fig. 2 is a similar view showing the parts in the position they assume while gas is burning; Fig. 3 is a detail showing a modification; Fig. 4 is an elevation on an enlarged scale of the electric sparking mechanism; and Fig. 5 is a perspective view of a detail.

In the illustrated embodiment there is combined a burner, an automatic igniting mechanism and novel means which operates upon a temporary rise in pressure to effect the lighting of the gas, and on a temporary drop in pressure to extinguish the same, and which, moreover, shall be responsive to such slight variations above or below the normal working pressure as not to materially affect the operativeness of other burners supplied from the same main.

Referring to the drawings by numerals, in which similar characters refer to corresponding parts throughout the several views, 1 represents a receptacle or tank, closed top and bottom by caps 2 and 2' and having a threaded socket 3 in the lower cap for the reception of the supply pipe 4 which is to be connected with gas mains or other source of supply.

Within tank 1 is an inverted bell 5, carrying a vertically disposed burner-tube 6 and a vertically disposed seal-tube 7, both extending exteriorly as well as interiorly of said bell, the former projecting loosely through an opening 2^a in the upper cap, and carrying a gas burner 8 and an igniter 9 (described in detail hereinafter) and the seal-tube 7 extending into a guiding tube or sleeve 10. The tube 7 is closed at its top, and the sleeve 10 is preferably covered by gauze to keep out dirt.

The burner-tube 6 which is open at its bottom and preferably is further provided with the lateral opening 6', is fixed to project well within bell 5 and surrounds a smaller tube or pipe 11 leading to the outside of tank 1 where it is provided with a threaded cap 12. Seal-tube 7 is also fixed to and extends well within bell 5. It is open at its lower end and surrounds a pipe 14 whose upper open end terminates just below the closed upper end of tube 7 and whose lower end communicates with supply

pipe 4. Tube 7 which terminates at a point below the lower end of tube 6, preferably is also provided with an auxiliary lateral opening 7'.

5 15 represents a body of liquid contained within tank 1, which may be supplied to said tank through tube or sleeve 10. In filling the tank, cap 12 is removed and liquid admitted until it begins to flow out 10 of pipe 11 when the cap 12 may be replaced; the overflow indicating that a proper working level has been reached within the tank. The working level of the liquid therefore is determined by the height of pipe 11 which 15 may be increased or diminished to suit varying conditions.

Referring to Fig. 1, it will be observed that the liquid level is the same in tank 1 and burner-tube 6 since both of these parts 20 are open to the atmosphere; the former through sleeve 10 and the latter through the valveless burner 8. The level in bell 5, however, is lower because of confined air or gas in the closed upper part of said bell, while 25 the level in seal-tube 7 is still lower, because of the pressure of gas therein, said tube, as before, explained, being in free communication with the gas main through pipe 14. The normal working pressure of the gas, 30 however, is insufficient to force the liquid in tube 7 as far down as opening 7', and inasmuch as said opening 7', as well as the opening 6' in the burner tube is covered by the body of liquid in bell 5, the gas is effectually 35 cut off from the burner.

To operate the lamp it is necessary to effect a temporary increase of pressure in the main, and this may be done by any preferred means; but since this forms no part 40 of the present invention, no illustration or detailed description thereof is deemed necessary.

Pressure in the main being increased, the liquid in tube 7 will be forced below opening 7' permitting the gas to escape through the body of the liquid to upper part of the bell. This action causes the bell to rise, carrying the burner-tube and the seal-tube with it. When the opening 6 rises above the 50 level of the liquid within the bell, the seal will be broken and the liquid contained within tube 6 will escape, permitting a restricted flow of gas to pass into said tube and drive out the air therein through the 55 burner. Further movement of the bell will cause the ends of both tubes 6 and 7 to be completely uncovered as shown in Fig. 2, permitting a free and unrestricted flow of gas from one tube to the other.

60 The upward movement of the bell is utilized to operate the igniter which, as hereinbefore mentioned, is mounted on the outer upper end of tube 6, and is so designed that its action will be delayed until after 65 the initial upward movement of the bell,

and the tube 6 has been cleared of air and pure gas is freely flowing.

I wish it to be understood that I reserve the right to use in combination with the above described devices, any form of igniter 70 that may be operated by the upward movement of the bell or its attached parts, the bell serving as a motor to operate the igniter.

I prefer, however, to use an electric spark-producing device such as shown, which comprises an outwardly extending resilient contact wire 16 normally lying outside of the flame zone but adapted to be sprung to juxtaposition to the vent or vents 8' of the 75 burner; a coacting contact finger 17 carried by a weighted rocking bell-crank lever 18; and connections for causing said lever to swing from one side to the other of the burner 8 on the rise of bell 5, and establish temporary electric connection between said finger 17 and said wire 16 en route.

The wire 16 which forms one terminal of an electric circuit (not shown) is supported by a curved bracket 19 which in turn is supported by a clamp 20 secured to the upper end of burner 8. Lever 18 comprises a long arm 21, a short arm 22 and a horizontal bearing portion 23, which latter is mounted on ears 24 forming part of a clamp 24' secured to the burner tube 6, but insulated therefrom. The arms 21 and 22 lie on opposite sides of the burner and the finger 17 which is substantially parallel with bearing portion 23 is located so as to pass over the 100 vents of the burner when the lever 18 is rocked in its bearings.

A second bell-crank lever comprising a long arm 25 and a short arm 26 and bearing portion 27 is also mounted independent of 105 the coacting contact 17 in the ears 24, as shown, the arm 26 lying beneath and supporting arm 21 of lever 18 in the unlighted condition of the lamp (see Fig. 1). Arm 25 is connected by a link 28 with a stationary part of the device, preferably a binding post 29 extending from clamp 30, secured to, but insulated from, sleeve 10. Binding post 29 is connected with one side of the electric circuit hereinbefore mentioned, but not 110 illustrated, and supplies current through the various arms and levers just described to contact finger 17.

When bell 5 rises, arm 25 is drawn downwardly and causes arm 26 to lift arm 21, the latter swinging in the arc of a circle and carrying contact finger 17 into engagement with wire 16, completing the electric circuit and bending wire 16 in the manner shown in dotted lines in Fig. 2. The time 115 required for finger 17 to reach wire 16 is sufficient for the tube 6 to be freed of air so that when said finger 17 snaps off wire 16 and the spark is formed, pure gas will be 120 flowing. Further movement of the bell 125

causes the arm 21 to swing past its pivotal center and fall by gravity to the full line position shown in Fig. 2 in which position it will be supported by the engagement of 5 arm 22 with arm 25.

With the parts in the position shown in Fig. 2, the temporary increase in gas pressure may be removed and normal pressure resumed without effect on the lamp, as the 10 weight of the bell is insufficient to force the gas back against such normal pressure, and the lamps will continue to burn as long as such pressure is maintained. When it is desired to extinguish the lamps, the pressure 15 in the mains will be lowered, whereupon the bell 5 will drop by gravity until the opening 7' passes below the level of the liquid 15, when the flow of gas to the bell will be shut off. The remaining gas will be forced out 20 by the continued descent of the bell and the lamps continue to burn until opening 6' is covered and the seal restored. The pressure in the mains may then be raised to normal without breaking the seal or disturbing the 25 relative arrangement of other parts of the device. When it is again required to light the lamps, the above operation will be repeated, it being understood that the descent of the bell will restore the parts of the ignition device to the position shown in Fig. 1.

The burner 8 may be of any construction suitable to the nature and volume of the gas used. Where burners of very small capacity are employed, it may be found advantageous to fit the burner-tube with a smaller inner tube leading to the burner, such as shown at 6² in Fig. 3, in order that the reduced quantity of air passing to the burner may have a proportionately reduced 40 volume of air to displace before the spark is applied.

6³ represents a small baffle plate attached

to the lower end of tube 6² to prevent the liquid 15 from splashing into said tube.

The function of tube or sleeve 10 is to 45 guide tube 7, and so prevent bell 5 from turning axially; and also to permit the end of supply pipe 14 to be carried high above the level of liquid 15.

It is to be understood that, in its broader 50 aspects, the invention is not limited to the particular construction shown and described as many changes in the details may be made without departing from the main principles 55 of the invention or sacrificing its chief advantages.

I claim:

An apparatus of the class described including in combination, a receptacle containing a suitable liquid, an inverted motor 60 bell sealed in said liquid, a gas supply pipe terminating within said bell above the level of said liquid, a seal-tube surrounding said supply pipe and having its upper end closed 65 and its lower end extended within the bell to cut off the flow from the supply pipe to the bell of gas under low pressure but permit such flow of gas under high pressure, a burner tube communicating with said bell 70 and adapted to be sealed from communication with the interior of the bell by said liquid when the flow of gas to the bell is cut off, said liquid being common both to said seal tube and to said burner tube accurately to control the flow of gas therebetween, and an igniter operated by said bell. 75

In testimony whereof, I have signed my name to this specification, in the presence of two subscribing witnesses.

CHARLES F. MASON.
